CLAIM

The ornamental design for a combined glove and watch, as shown and described.

DESCRIPTION

FIG. 1 is a top plan view of a combined glove and watch showing my new design;

FIG. 2 is a right side elevational view thereof;

FIG. 3 is a bottom plan view thereof;

FIG. 4 is a front elevational view thereof; and
The cross-hatch shading shown in FIGS. 2 and 3 is
understood to repeat throughout the indicated area.

FIG. 5 is a rear elevational view thereof.

The broken lines in FIGS. 1, 2 and 3 represent conventional stitching.
